UNITED STATES PATENT OFFICE.

ANDREW J. HUBBARD AND CARL A. SWANSON, OF JACKSONVILLE, ILLINOIS.

PNEUMATIC PUMP.

1,109,419.

Specification of Letters Patent.

Patented Sept. 1, 1914.

Application filed December 26, 1912. Serial No. 738,607.

To all whom it may concern:

Be it known that we, ANDREW J. HUBBARD and CARL A. SWANSON, citizens of the United States, and residents of Jacksonville, in the county of Morgan and State of Illinois, have made certain new and useful Improvements in Pneumatic Pumps, of which the following is a specification.

Our present invention relates to pneumatic pumps for the purpose of forcing water from a well or cistern to any part of a building, by means of compressed air, without the use of a storage tank, so that the water will be fresh at all times and ready 10 for use at any point desired, and the object of our invention is to provide a generally improved construction which will do away with all packed joints, springs and diaphragms, and will also do away with all 15 valved or mechanical parts exposed to the weather.

Other objects of our present invention have to do with certain specific features of our construction and will be hereinafter 20 specifically referred to, one specific object being for instance, to provide a piston which is acted upon by the compressed air and which may effectively operate without the use of the usual cup leathers.

Our improved invention is shown in the accompanying drawings which form a part of this specification, and in which—

Figure 1 is an elevation of our complete apparatus. Fig. 2 is a small vertical section 30 through the entire mechanism at the upper ends of the water chamber. Fig. 3 is a plan view, and Fig. 4 is a partial vertical section taken substantially on line 4—4 of Fig. 2.

Referring now to these figures, we provide 40 a pair of tubular upright tanks A, B which are arranged side by side and which are rigidly connected at their upper ends. These tanks which constitute water chambers, are provided at their lower ends with the usual 45 submerged intake or foot valves a and b respectively and are also provided with exterior upwardly extending water outlet pipes a' and b' respectively leading from a point adjacent their lower ends. The water 50 outlet pipes a' and b' are connected at their upper ends to a common or main pipe C by means of which the water taken from the chambers is led to desirable points throughout the house or other building in connection with which our improved pump is utilized for use.

The main air pipe D which is provided with controlling devices at various points (not shown) leads to a central point of a valve casing E, this casing having a base e 60 provided with ports e' and e^2 , these ports being arranged upon opposite sides of a central vertical aperture e^3 . From the port e' extends a branch air supply pipe D' which is arranged to communicate at its lower end 65 with a water chamber A, and from the opposite port e^2 extends a branch air pipe D ^{2} which is arranged to communicate with the water chamber B, both of these pipes being let into the tops of the water chambers as 70 clearly shown in Figs. 1 and 2.

Below the base e of the valve casing E is formed a transverse piston cylinder F, the ends of which are closed by caps f and f' , and which is provided with a central side 75 exhaust f^2 with which the upwardly extending exhaust pipe f^3 communicates. Mounted within the cylinder F is a movable piston comprising a shaft or rod G and spaced 80 disks or heads g and g' , which are arranged upon opposite sides of the exhaust f^2 . Slidably disposed within the valve casing is a valve G', this valve being arranged to cover the upper end of the aperture e^3 and being connected by means of a rod G ^{2} to the rod G 85 of the piston, said connecting rod G ^{2} being arranged through the said aperture e^3 , which as will be clearly seen from Fig. 2 communicates between the interior of the slide valve 90 G' and the central portion of the piston cylinder F between the piston heads g and g' and consequently communicates with the exhaust f^2 . In its position as shown in Fig. 2 the slide valve G' laps the port e^2 with the aperture e^3 , thus registering the water chamber B with the exhaust f^2 at the time when the port e' registers with the water chamber A with the main air supply pipe D, and in 95 the other and opposite position of the slide valve, the action will be reversed.

The ends of the piston rod G are threaded and the heads or disks g' are secured in position against shoulders g^2 by means of nuts g^3 , each end of the piston rod just mentioned receiving an adjustable internally 100 threaded sleeve g^4 within which is screwed an adjusting member g^5 which abuts the end of the rod. Adjacent its opposite ends and beyond the extreme positions of the heads or disks g and g' the piston cylinder communicates, through ports f^1 and f^5 , with the upper ends of pipes H and H', the lower ends 110

of which extend into the upper portions of the water chambers A and B respectively. Thus, with the parts in position as shown in Figs. 1 and 2, compressed air is admitted 5 through the main air pipe D and through the valve members e' and branch pipe D' to the upper portion of the water chamber A, the water within which is thereby forced outwardly and upwardly through the outlet pipe a' and through the main water pipe C. Means are provided so that when the water in the chamber A becomes exhausted, the piston within the cylinder F is displaced 10 to the right in Fig. 2 lapping the port e' with the exhaust aperture e² and at the same time registering the port e² with the main air pipe D, this action resulting in the air being led through ports e² and through the branch pipe D² to the upper portion of the 15 water chamber B from which water is forced through pipe b' to the main water pipe C, at the same time permitting the air accumulated within the water chamber A to exhaust through its pipe D' and through 20 slide valve G' and aperture e³ to the exhaust pipe f³. The means for accomplishing this result resides in float members I, one of which is arranged in each of the chambers A and B and provided with an upwardly extending stem i, projecting and guided within a tube j depending from a valve casing J secured upon the lower end of the respective pipe H and H'. Each of the valve casings J has a side aperture j' and a valve seat j² 25 at the lower end of its respective pipe H and H', the respective float stem i having an upper tapering end i' which is adapted to cooperate with the valve seat j² and which is held upon the seat as soon as there is sufficient water within the respective water chamber to sustain the float I. As soon thereafter, as the water level in one of the chambers is lowered to such an extent that its float I may drop, the valve i' will be 30 moved from its seat and the air which is being forced within the water chamber may find its way through the opening j' and the valve and upwardly through the pipe H or H' and the piston cylinder port f⁴ or f⁵ 35 whereby to force the piston toward the relatively opposite end of the piston cylinder. Thus while one of the water chambers A and B is being acted upon by the air to discharge its water the other water chamber is taking 40 in water through its foot valve a or b. The operation above described may thus be continued and the water chambers alternately discharged to supply the demand for water, the shifting from one chamber to the other 45 being entirely automatic as described. After the piston has been moved toward one end of the piston cylinder there will be considerable air pressure confined between one end thereof and the end of the cylinder and 50 considerable difficulty might be experienced

to cause its reverse movement upon the next operation. In order to obviate this difficulty we provide a port f⁶ midway of the piston cylinder F and at the lower portion thereof, which port thus communicates with the exhaust f² and its pipe f³. This port f⁶ is in communication with laterally extending pipes K and K', which pipes respectively communicate through the sides of the pipes H and H' and with depending tubes k in such pipes H and H'. In each of the pipes H and H' there is also formed a valve seat h and between this valve seat h and the lower end of the tube k is movable a double ended valve member k', the upper end of which is tapered so as to close the lower end of the tube k and the lower end of which is formed to seat upon the valve seat h. Thus when air is admitted through the lower end of either of the pipes H and H' through the action of the float valve as before described, the valve member k' within the respective pipe is raised and its upper end closes the lower end of the tube k, permitting the air to pass up into the piston cylinder without opposition. On the other hand, when the piston is moved toward one end of the piston cylinder, the previously supplied air to that end of the piston is forced down into the respective pipe H and H' and causes the valve member k' to lower and seat upon the seat h. The air is then free to pass up through the tube k and thence through the respective pipe K and K' and the port f into the central portion of the piston chamber and thence upwardly through the exhaust f³. 55

We claim:—

1. In a pneumatic pump, the combination of a pair of water chambers, having submerged foot valves and water outlet pipes, a piston cylinder having a central exhaust, a piston therein comprising spaced heads upon opposite sides of the exhaust, connections between the cylinder ends and the upper portions of the water chambers and having valves normally closing the same, float members within the water chambers and controlling the said valves, a valve chamber adjacent the piston chamber and carrying a central port communicating with the upper portions of the cylinder exhaust, and side ports connecting to the valve chamber, an air supply pipe leading to the valve chamber, and a slide valve having connection with the piston and movable therewith to alternately register one of the valve side ports with the exhaust. 110

2. In a pneumatic pump, the combination of a pair of water chambers having submerged foot valves and water outlet pipes, a main air supply pipe, a valve casing with which the said main air pipe communicates and which is provided with said ports branch air pipes leading from said ports to the upper portions of the water cham- 115 120 125 130

bers, said casing also having the central exhaust port, an air controlling valve movable in said casing to alternately register one of said side ports with the exhaust port, a valve actuating member having connection with said valve, a casing within which said member is movable, connections between opposite ends of said last named casing and the upper portions of the water chambers whereby air may be admitted to the casing to move the actuating member toward opposite ends thereof, the lower ends of said connections having valve seats, and floats arranged in the water chambers and having upwardly projecting stems provided with tapered upper ends forming valves and adapted to coöperate with the said seats.

3. In a pneumatic pump, the combination of a pair of water chambers, having submerged foot valves and water outlet pipes, a piston cylinder having a central exhaust, a piston therein comprising spaced heads upon opposite sides of the exhaust, connecting pipes between the cylinder ends and the upper portions of the water chambers, and having intermediate valve seats and side ports above said seats, tubes depending in said pipes and having their upper ends communicating with said side ports, doubled ended valve members movable between

said valve seats and the lower ends of the tubes and adapted to coöperate therewith, said connecting pipes also having lower valves, float members within the water chambers and controlling the said lower valves, a valve chamber adjacent the piston chamber and having a central port communicating with a cylinder exhaust and side ports communicating with the upper portions of the water chambers, an air supply pipe leading to the said valve chamber, and a slide valve having connection with the piston and movable therewith to alternately register one of the valve side ports with the exhaust.

4. In a device of the character described, a piston comprising a stem having threaded end portions, heads secured upon said stem in spaced relation, adjusting sleeves 50 which are alternately threaded and adapted to be screwed upon the threaded end portions of the stem to selected positions, and externally threaded adjusting nuts adapted to be screwed within the said sleeves and 55 to abut the ends of the stem of the piston, substantially as described.
